UNITED STATES PATENT OFFICE.

FREDERICK LAMPLough, OF FELTHAM, ENGLAND, ASSIGNOR TO HYDRO-DYNAMICS, LIMITED, OF LONDON, ENGLAND.

HYDRAULIC ENGINE.

1,341,328.

Specification of Letters Patent.

Patented May 25, 1920.

Application filed April 28, 1919. Serial No. 293,370.

To all whom it may concern:

Be it known that I, FREDERICK LAMPLough, a subject of the King of England, residing at Feltham, in Middlesex, England, 5 have invented certain new and useful Improvements in Hydraulic Engines, of which the following is a specification.

This invention is for improvements in or relating to hydraulic engines of the type 10 comprising a rotatably mounted driven member, a plurality of engine-cylinders or pairs of cylinders carried by said member and having their longitudinal axes transverse thereto, oppositely moving pistons in 15 said cylinders, and a planet-wheel operatively connected to each piston and gearing with a sun-wheel co-axial with the driven member.

According to this invention, an engine of 20 the type just described is constructed to have the cylinders arranged in pairs, both open-ended and communicating at their inner ends with a chamber common to both, said cylinders preferably being disposed with 25 their longitudinal axes inclined to one another in a wide V whose point is directed radially outward from the driven member.

In the accompanying drawings which 30 illustrate one construction of hydraulic engine according to this invention:—

Figure 1 is a longitudinal section on the line 1, 1 of Fig. 2;

Fig. 2 is a transverse section on the line 2, 2 of Fig. 1, and

Fig. 3 is an end elevation.

Like reference characters indicate like parts throughout the drawings.

A fixed shaft A has rotatably mounted upon it a casing or chamber B which has 40 three radially disposed chambers B¹ B² B³ communicating with it, by ports or openings B⁴. The shaft A is cut away as shown in Fig. 2 to constitute a valve controlling these 45 ports as the casing B rotates, allowing them to communicate alternately with inlet and outlet passages A¹ A² formed in the shaft A.

Within each of the chambers B¹ B² B³ there are formed two cylinders C¹ C² which are open at their inner ends to the interior 50 of their respective chambers, but at their outer ends are open into the general casing D inclosing the whole mechanism. Pistons E E¹ respectively are mounted in these cylinders. It will be seen that the cylinders

are arranged in pairs with their open ends 55 pointing away from one another in a wide V, the point of the V being directed radially outward. This is the preferred construction, as it gives the most compact form of engine, but it will be appreciated that this 60 particular arrangement is not essential, and that changes may be made therein within the scope of the appended claim without departing from the spirit of the invention.

The casing D carries three crankshafts F 65 arranged one between each pair of the chambers B¹ B² B³, these crankshafts having each two throws and having their longitudinal axes parallel with that of the shaft A. With the above described arrangement of cylinders, it will be seen that each crankshaft is faced by two cylinders, one in each of the chambers B¹ B² and B³ adjacent to it, and the pistons in these cylinders are coupled by suitable connecting rods to the cranks or 75 throws on the shaft.

At the outer end of each shaft (the right hand end of Fig. 1) there is keyed or otherwise rotatively secured a spur-wheel G which constitutes the planet-wheel of an 80 epicyclic gearing, the sun-wheel H being secured on the fixed shaft A and always stationary. The crankshafts F are preferably mounted in ball-bearings F¹.

On the end of the chamber B is secured in 85 any desired manner a shaft B⁵ which constitutes the driven shaft of this engine, i. e. the shaft to which it supplies power by its rotation.

The operation of this engine is as follows:—

Oil driven from the primary engine into the central chamber B through the inlet-conduit A¹ enters one of the cylinder chambers B¹, B² or B³ and thus thrusts the two 95 pistons E E¹ in the two cylinders C¹ C² outward. This imparts movement to the planet-wheels G on opposite sides of the pair of cylinders and thus the driven member B B⁵ is made to rotate around the sun-wheel H. Its movement changes the position of the ports B⁴ in the valve-chamber B relatively to the stationary valve-member A and thus the one cylinder-chamber is exhausted and another one is filled so that the 105 rotary movement of the driven-member is maintained so long as the flow of the oil from the primary engine is maintained.

Obviously the rate at which the secondary engine rotates depends on the rate at which it is supplied with the operating fluid. It will also be appreciated that this engine is 5 reversible by the simple means of reversing the inlet and outlet passage, *i. e.* by reversing the direction of the flow of the operating fluid through it.

The object of this invention is to provide 10 a secondary engine, that is, one driven by a prime-mover of the same type, which shall be more compact than has heretofore been possible and wherein the operating parts shall be so balanced that the central shaft 15 is relieved of side-thrust from the same. As is well-known these secondary engines are driven by fluid circulated through them by a primary engine which is itself driven by some outside source of power, such as an 20 electric-motor.

What I claim as my invention and desire to secure by Letters Patent is:—

In an engine of the type described, a stationary valve shaft, a ported casing rotatably mounted on said shaft, a plurality of 25 pairs of open ended cylinders formed in said casing and communicating at their inner ends with a chamber common to both cylinders of each pair, a piston in each of said cylinders, said cylinders each having one 30 end open to receive motive fluid from said valve shaft through said ports, crank shafts journaled in said casing and operatively connected to said pistons, and means operatively connected to said crank shafts for operating the casing when motive fluid is supplied thereto, substantially as described.

In testimony whereof I affix my signature.

FREDERICK LAMPLough.
